UNITED STATES PATENT OFFICE.

PHILIP F. KRUG, OF NEW YORK, N. Y.

CONTROL FOR FIRE-SHUTTERS.

1,177,711.

Specification of Letters Patent.

Patented Apr. 4, 1916.

Original application filed July 13, 1914, Serial No. 850,535. Divided and this application filed October 26, 1914. Serial No. 868,691.

To all whom it may concern:

Be it known that I, PHILIP F. KRUG, a citizen of the United States, and a resident of the city of New York, borough of Brooklyn, county of Queens, and State of New York, have invented certain new and useful Improvements in Control for Fire-Shutters, of which the following is a specification.

10 My invention relates in general to a moving picture machine and particularly relates to a control for automatically opening the fire shutter of such a machine when the rotary parts of the film feeding mechanism have reached a preset speed.

This application constitutes a division of my application, Serial No. 850,535, filed July 13, 1914.

One of the objects of my invention is to 20 provide a simple and automatically controlled device of the above indicated character, which will be positive in its action in opening the shutter and which will permit the prompt and automatic closing of the 25 shutter when the speed of the film feeding mechanism has fallen below the preset speed at which the device may be safely operated.

I attain the above outlined objects broadly 30 by providing a rotary member having diametrically movable weighted parts normally held in retracted position by a suitable spring and adapted to be actuated by the centrifugal force of rotation of the member 35 to move against the resistance of the spring and into a frictional clutching engagement with a shutter actuating part.

Various other objects and advantages of 40 the invention will be in part obvious from an inspection of the accompanying drawings and in part will be more fully set forth in the following particular description of one 45 form of mechanism embodying the invention and it also consists in certain new and novel features of construction and combination of parts hereinafter set forth and claimed.

Referring to the accompanying drawings: 50 Figure 1 shows a fragmentary portion of a moving picture machine head in side elevation with a preferred embodiment of my invention attached thereto; and Figs. 2 and 3 are respectively longitudinal and 55 transverse sectional views through the shutter control shown in Fig. 1.

In the drawings there is illustrated a moving picture machine head including a main driving shaft 11 which has a main driving wheel 12 mounted thereon. A feed sprocket shaft 13 has a feed sprocket 14 mounted thereon and driven directly from the gear wheel 12 by means of a relatively small gear wheel 15. The film 16 is continuously fed into the upper loop 17 from which it passes through the usual frictional holding means 18 about the picture aperture 19 such as is usual in devices of this character. A weighted fire shutter 40 has its upper edge pivoted to the machine in rear of the picture aperture 19 and is actuated by means of a link 41 attached to the outer rim 42 of a shutter control 43 mounted on the feed sprocket shaft 13. This control includes a disk 44 keyed to the shaft 13 and concentrically mounted within the rim 42 of an enclosing cylindrical shell mounted loosely on the shaft 13. The disk has a plurality of diametrically disposed recesses 45 opening to the periphery thereof, which recesses each contain a heavy sliding block 46 movable out of the recess under centrifugal force of the rotating shaft 13. Disposed between the periphery of the disk 44 and the inner surface of the rim 42 is a single coiled spring 47, the tendency of which 85 spring is to wrap itself closely about the periphery of the disk bearing on the blocks 46. It has been found in practice that the spring need have but a single coil even less than 360° and is preferably made 90 very light.

In operation, and with the parts in the position shown in Fig. 1, the actuation of the shaft 13 causes the weights 46 in the shutter control 43 to move outward under 95 centrifugal force and act on the coil spring 47 to bind the same against the rim 42 causing the same to rotate over an arc and act upon the link 41 to move the shutter into open position. Reducing the speed of 100 rotation of the shaft 13 correspondingly reduces the tension on the weights 46, permits the spring 47 to contract out of engagement with the rim 42, thus allowing the shutter 40 to fall by gravity into its 105 closing position intercepting the passage of light through the machine as is usual with devices of this character.

It is obvious that by means of a device of this character most of the wear is taken up 110

by the spring 47 which may readily be replaced when worn. By varying the length of this spring its clutching action may be accurately adjusted so as to become operative at any particular speed of the film feeding mechanism.

The device may be readily and cheaply constructed as there is no necessity of refined milling or interfitting of parts, it being merely necessary to roughly drill the recesses 45 to produce a guide for the blocks 46.

While I have shown and described, and have pointed out in the annexed claim, certain novel features of my invention, it will be understood that various omissions, substitutions and changes in the form and details of the device illustrated and in its operation may be made by those skilled in the art without departing from the spirit of the invention.

Having thus described my invention, I claim:—

In a moving picture machine, a fire shutter control comprising a rotary disk having

a plurality of diametrically disposed recesses in the periphery thereof, a plurality of weighted blocks, each having a sliding fit in one of said recesses and movable outwardly under the centrifugal force of the 30 rotating disk, a band surrounding the periphery of the disk and having a slipping fit thereon, guiding means engaging the band to prevent transverse movement thereof, a 35 spring coiled about the disk and normally disposed with all portions thereof engaging the disk and spaced within the band, the diameter of said spring adapted to be enlarged by the centrifugal action of the weighted blocks thereby to bring the spring 40 into frictional engagement with the band and a shutter actuating member operatively connected to said band.

Signed at New York city, in the county of Queens and State of New York this 20th 45 day of October A. D. 1914.

PHILIP F. KRUG.
